R. BENTLEY

REMOVABLE DECK FLOOR FOR LIVE POULTRY CARS

Original Filed April 12, 1923

Inventor

R. Bentley.

By *Alfred J. Randolph* Attorney

UNITED STATES PATENT OFFICE.

ROY BENTLEY, OF SABETHA, KANSAS, ASSIGNEE TO FRANK X. MUDD, OF CHICAGO,
ILLINOIS.

REMOVABLE DECK FLOOR FOR LIVE-POULTRY CARS.

Application filed April 12, 1923, Serial No. 631,615. Renewed August 26, 1925.

To all whom it may concern:

Be it known that I, ROY BENTLEY, a citizen of the United States, residing at Sabetha, in the county of Nemaha and State of Kansas, have invented certain new and useful Improvements in Removable Deck Floors for Live-Poultry Cars; and I do hereby declare the following to be a full, clear, and exact description of the invention, such as will enable others skilled in the art to which it appertains to make and use the same.

The present invention relates more particularly to cars for transporting live poultry and has for its object to facilitate the cleaning of the deck and the removal of dead fowl, as well as to prevent the stock from smothering under troughs.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a perspective view of a removable floor for the deck of a live poultry car embodying the invention, and

Figure 2 is a fragmentary view taken longitudinally of a car showing my improvement in use, and

Figure 3 is a section taken on the line 3—3 of Figure 1.

Corresponding and like parts are referred to in the following description and designated in the several views of the drawings by like reference characters.

The removable floor comprises a sheet

metal plate 1 preferably of galvanized iron

and of required dimensions as occasion may require. Guards 2 are provided at opposite sides of the plate 1 and may be of any height to retain the poultry and to provide ample ventilation, whereby to prevent smothering under the troughs A in a car. The side guards 2 preferably form a part of the plate 1, marginal portions thereof being bent upwardly and parts cut therefrom to insure a circulation of air. A handle 3 is provided at the front of the plate 1 for convenience of drawing the same outwardly from the car when it is required to clean the deck or unload the car. A rear guard 4 is provided and is of a height to prevent the fowl from getting thereover and to insure moving the same to the side of the car when drawing the floor outwardly over the deck for purposes of cleaning, unloading or removing any dead fowl. The rear guard 4 consists of brackets 5 and rods 6, the brackets being of L-form and secured to the plate 1 and the rods 6 being attached to the upright portion of the bracket.

In practice, a floor constructed substantially as herein indicated is placed upon the deck of the poultry car and may be drawn outwardly when it is required to clean or unload the car as herein indicated.

What is claimed is:

In combination with a car for transporting live poultry, the car having spaced troughs and supports therefor, a movable floor, said floor having relatively low open portions integral with it at its sides rising therefrom and constituting guards serving as the sole means to prevent escape of poultry below the troughs, brackets rising from the floor at the rear thereof, and rods mounted by said brackets above the guards, said rods being of a length greater than the distance between the supports.

In testimony whereof I affix my signature.

ROY BENTLEY.
